UNITED STATES PATENT OFFICE.

FREDERICK O. GAMBLE, OF CHICAGO, ILLINOIS.

TOOL FOR USING DENTAL FLOSS.

1,110,680.

Specification of Letters Patent. Patented Sept. 15, 1914.

Application filed November 20, 1912. Serial No. 732,412.

To all whom it may concern:

Be it known that I, FREDERICK O. GAMBLE, a citizen of the United States, residing at Chicago, in the county of Cook and State of Illinois, have invented new and useful Improvements in Tools for Using Dental Floss, of which the following is a specification, reference being had to the accompanying drawings, forming a part thereof.

10 The purpose of this invention is to provide a convenient tool with which dental floss may be held and manipulated for the customary purpose for which such floss is used; viz., cleaning and removing obstructions from between the teeth.

15 It consists in the elements and features of construction shown and described as indicated in the claims.

20 In the drawings:—Figure 1 is a partly sectional plan view of a tool embodying this invention, section being made at the line 1—1 on Fig. 2. Fig. 2 is an edge elevation of the same. Fig. 3 is an edge elevation of one of the members of the tool. Fig. 4 is 25 an edge elevation of the other member. Fig. 5 is an axial section of the bobbin for holding the floss. Fig. 6 is an elevation of one of the floss-holding clamps with its stem or spindle. Fig. 7 is a detail section at the 30 line 7—7 on Fig. 2. Fig. 8 is a side view and Fig. 9 is an edge view of a modified form of terminal of the spreader arm.

35 The tool embodying this invention comprises two members, 1 and 2, which are pivoted together, as seen in Fig. 1, each member comprising a floss-holding spreader arm, A, and a handle, B, extending oppositely from the pivot, the handle and spreading arm of each member being at an obtuse 40 angle to each other, the two members being pivoted together with the obtuse angles opening away from each other, so that when thus pivoted the closing together of the handles operates to separate the spreader 45 arms. Each of the members, 1 and 2, has the middle portion of its length at which the pivot is located offset along the pivot axis from the other member, so that when the two members are applied to each other 50 and connected by the pivot at said offset portions there is formed between them a space extending for a short distance radially from the pivot, in which there is accommodated a bobbin, 3, mounted on the pivot stud, 4. 55 Said pivot stud is rigid with the member, 1, and it has a head, 4^a, back of which it is re-

duced in diameter in a direction transverse to the length of the member, 1, by cutting away a small segment at each side, leaving it at that point of the form shown in Fig. 7. 60 The member, 2, has a pivotal aperture, 2^b, for receiving the stud, 4, of the full diameter of said stud back of its head; that is, without regard to said reduction; and said pivotal aperture, 2^b, is entered by a slot, 2^c, 65 leading radially thereinto, said slot being of a width to admit the reduced portion of the stud, 4, the two members being therefore susceptible of being assembled by entering the pivot stud through the slot, 2^c, when 70 the two members are substantially at right angles to each other. Being thus assembled, they are retained against separation by turning the one member upon the other into operative position, as shown in Fig. 1. The 75 bobbin, 3, has its central aperture, 3^a, large enough to be passed over the head, 4^a, of the stud, 4; and this being done before the two members are assembled in the manner described, the bobbin is thus loosely carried 80 on the pivot stud, 4.

The members 1 and 2, are formed with disks, 1^d and 2^d, respectively, concentric with the pivot apertures, the slot, 2^c, cutting through the disk, 2^d, to its edge, and 85 the bobbin, 3, is of such dimension as to be pressed slightly between the circumference of these disks when the tool is fully assembled, so that it is frictionally restrained to prevent too free rotation in 90 service. The dental floss, represented at 6, runs from the bobbin along the edge of the spreading arm of the member, 2, lying in a groove, 2^e, in said arm, and passing through an eye, 2^f, at the end of the arm, 95 thence across the gap between the ends of the two spreading arms through an eye, 1^g, in the end of the arm of the member, 1, back in a groove, 1^e, in the outer edge of the arm of said member, 1. On each arm, 100 lodged in the groove thereof, there is provided a clamp comprising a head, 7, having its under side corrugated, and a stem, 8, which extends through the arm and has coiled around it on the inner side of the 105 arm a spring, 9, stopped against a nut, 10, riveted on the inner end of the stem; and there is pivoted at the bottom of the groove, adjacent to the aperture in the arm through which the stem, 8, extends, a corrugated 110 shoulder, 11, which matches the corrugated shoulder of the head, 7 so that the floss.

6, passing between the two corrugated shoulders is firmly gripped by the pressure of the spring, 9. The floss being threaded into the tool in the manner thus described 5 and shown in Fig. 1, it is in condition for use, the handles being grasped between the thumb and finger of the user after the manner of handling a pair of scissors, but with this difference,—that pressing the two 10 handles together by the thumb and fingers spreads the arms at the opposite ends and stretches the floss between the two eyes, 1^g and 2^g, so that it can be introduced and drawn back and forth between the teeth 15 for the usual purpose for which dental floss is thus employed. When a portion of the floss becomes mutilated so that a new portion must be brought into service, the operator, slightly spreading the handle 20 ends, will slack the floss, and then taking hold of the end of the floss which protrudes beyond the clamp in the arm, 2, he can draw the floss through both clamps and the eyes, 1^g and 2^g, bringing the desired fresh portion 25 into the space between the two arms. For retaining the floss securely, as described, it passes through guide eyes in the stems of both the clamps, and for conveniently introducing the floss into these guide eyes, 30 the guide eye in each stem is made in the form shown in Fig. 6; that is, in the form of an angle slot, 11, opening at the side of the stem and extending into the axis and then longitudinally to the corrugated shoulder. For threading the floss into the tool, 35 the two handles will be slightly spread until the nuts on the inner ends of the stems, 8, of the clamps coming into contact, cause both clamps to be forced outward against the resistance of the springs sufficiently to uncover 40 the mouths of the guide eyes, 11, so that the floss may be introduced laterally threinto between the corrugated rolls.

It may be found desirable in some cases 45 to make the spreader arms self-threading at the terminals; and for that purpose, the form of construction shown in Figs. 8 and 9 may be employed. This modification consists in splitting or forking the end of the spreader arm to make a thread entrance, 15, and forming each of the fork members, 16, as a hook, the two hooks turning in opposite directions, as clearly seen in Fig. 9. The thread will then be introduced through the rift, 15, and turned crosswise thereof, to engage both hooks.

I claim:—

1. A device for the purpose indicated, 50 comprising two members and a pivot at which they are connected, each having a handle and a spreading arm extending in opposite directions from the pivotal connection, said handle and arm of each member being at the same side of a plane which 55 contains the axis of the pivot and which

extends between the two handles, whereby the approach of the handles separates the spreading arms; a bobbin mounted upon one member, the spreading arms having terminal thread guides to receive the thread from 70 the bobbin, and thread clamps on the spreading arms, respectively, back of the thread guides.

2. A device for the purpose indicated, 75 comprising two members and a pivot at which they are connected, each having a handle and a spreading arm extending in opposite directions from the pivot, the handle and arm of each member being at the same side of a plane which contains the axis 80 of the pivot and which extends between the two handles, whereby the approach of the handle separates the spreading arms, the handles being offset from each other in the direction of the axis of their pivotal connection to permit them to pass by each other, the pivot being a stud mounted upon one member having a head, and a portion back of the stud oblong in cross-section, the other member having a pivot bearing whose diameter is equal to the longer dimension of 85 said oblong portion, and a slot leading into said bearing whose width is less than the longer and adapted to accommodate the shorter dimension of said oblong portion, 90 said longer dimension and said slot being positioned on the respective members transversely to each other at all operative positions of the device.

3. A device for the purpose indicated, 100 comprising two members and a pivot at which they are connected, each having a handle and a spreading arm extending in opposite directions from the pivot, the spreading arms being directly opposed to 105 each other in their respective paths of their movement about the pivot axis, the handle and arm of each member being at the same side of a plane which contains the axis of the pivot and which extends between the two 110 handles, whereby the approach of the handle separates the spreading arms, the handles being offset from each other in the direction of the axis of their pivotal connection to permit them to pass by each other, 115 the pivot being a stud mounted upon one member having a head and a portion back of the stud oblong in cross-section, the other member having a pivot bearing whose diameter is equal to the longer dimension of 120 said longer portion, and a slot leading into said bearing whose width is less than the longer and adapted to accommodate the shorter dimension of said oblong portion, 125 this longer dimension and said slot being positioned on the respective members at an angle to each other greater than the angle between the handles at the closed position of the spreading arms; whereby the handles must be lapped past each other in order to 130

- bring said slot and longer dimension in alinement.
4. A device for the purpose indicated, comprising two pivotally-connected members each having a handle and a spreading arm extending in opposite directions from the axis of said connection, said handle and arm of each member being at the same side of the plane which contains said axis and which extends between the two handles; a bobbin mounted for turning about said axis, each spreading arm having a terminal thread guide and clamps on each arm back of the thread guides.
5. A device for the purpose indicated comprising two members and a pivot at which they are connected, each having a spreading arm and an operating handle; each of the spreading arms having a thread guide; thread clamps mounted upon the spreading arms, respectively, back of the thread guides, each clamp having a stem extending through the arm, said stems being opposed to each other between the arms and of such length that they meet when the spreading arms approach each other within a predetermined distance, and springs which hold the thread clamps against the arms to clamp the thread.
6. A device for the purpose indicated, comprising two members and a pivot at

which they are connected, having, respectively, spreading arms extending divergently from the pivot, said spreading arms having terminal thread guides and grooves leading to said terminal guides; a bobbin mounted 35 for rotation about the pivot, the thread groove of one of the spreading arms leading to its inner side for receiving the thread from the bobbin.

7. A device for the purpose indicated, 40 comprising two members and a pivot at which they are connected, each having a handle and a spreading arm, each of said members being offset from the other at the vicinity of the pivot; a bobbin mounted on 45 the pivot and accommodated in the offset portions of said members, each of the spreading arms having a terminal thread guide and a thread groove in the outer side of the arm leading to said guide, said groove in one 50 of the spreading arms extending to the offset portion thereof for receiving the thread from the bobbin.

In testimony whereof, I have hereunto set my hand, at Chicago, Illinois, this 16 day of 55 Nov., 1912.

FREDERICK O. GAMBLE.
